UNITED STATES PATENT OFFICE.

JOHN L. DINSMOOR, OF BROOKLYN, NEW YORK, ASSIGNOR TO ANCHOR CAP & CLOSURE CORPORATION, OF BROOKLYN, NEW YORK, A CORPORATION OF NEW YORK.

SHACKLE-SEAL.

1,369,010.

Specification of Letters Patent. Patented Feb. 22, 1921.

Application filed January 27, 1920. Serial No. 354,367.

To all whom it may concern:

Be it known that I, JOHN L. DINSMOOR, a citizen of the United States, residing at Brooklyn, in the county of Kings, State of New York, have invented certain new and useful Improvements in Shackle-Seals, of which the following is a specification.

This invention relates to shackle seals of the type commonly designated "snap seals".

10 The general object of the invention is the provision of a seal of this description which possesses the elements of security necessary in a device of this type, and which may be manufactured at minimum cost and 15 applied with a simple operation which does not require the use of a tool.

More specifically stated, the objects of this 20 invention include the provision of a seal which may be made up entirely from light sheet-metal by punching and folding operations.

Another of such objects contemplates the 25 provision of a seal of the sort specified which may be folded out of sheet-metal in such fashion that the locking members whereby the seal is closed are entirely protected from tampering, and the seal presents no exterior seams or joints which might be opened to disengage and reengage the locking members.

30 A further object contemplates the provision of a seal which may be formed out of sheet-metal and wherein the folding together of the keeper and shackle members 35 provides an inclosure for the interengaging locking members, and the engagement of said locking members retains all of the parts against unfolding.

Described generally, the invention contemplates 40 the provision of a keeper member and a shackle member. Both of these articles may be formed out of very light sheet-metal by folding and punching operations, the keeper being folded to form a substantially 45 rectangular housing open at opposite ends, and the terminal folds of the metal forming the walls being overlapped. The shackle is formed of a straight strip of sheet-metal or the like of proper width to fit accurately 50 in the keeper. Adjacent its respective extremities the shackle is provided with locking members adapted for interengagement when the seal is assembled and applied, effective to prevent the parts being discon-

nected. In the assembling of the device 55 the shackle is threaded through the keeper twice, being folded about the overlapped folds of the latter, thereby binding them together and effectively covering the external margin of the metal to prevent its being 60 tampered with. This form of assembly 65 disposes certain of the locking members on the shackle within the housing, and incloses them from access from the ends of the housing. When the shackle is applied the other 70 extremity is inserted into the end of the housing between folds of the shackle already in place and the locking members automatically engage when the parts are placed in proper position. This effectively 75 secures the shackle and incloses the interengaging locking members, the engagement of which prevents unfolding or withdrawal of the shackle and thereby retains the keeper in its folded condition and the parts in fixed 80 assembly.

The invention may be understood more fully by reference to the accompanying drawings in which one embodiment thereof is shown for the purpose of illustration. It 85 will be understood, of course, that various advantageous modifications and adaptations may be made in the structure illustrated and now about to be described without departing from the scope and spirit of the invention involved.

In the said drawings Figure 1 represents a perspective view of the keeper.

Fig. 2 a fragmentary perspective view of the shackle;

Fig. 3 an enlarged longitudinal section through the shackle and keeper in their assembled relationship before the attachment or locking of the seal;

Fig. 4 is an enlarged longitudinal sectional view of the device taken through the assembled keeper and shackle showing the relationship of parts when the seal is closed and locked; and

Fig. 5 is a plan or top view of the assembled keeper and shackle illustrating the form in which the device is supplied to the user.

Referring to these drawings in detail by means of the reference characters applied, let it be understood that the character A designates generally the keeper, and the character B designates generally the shackle.

The keeper is formed from light ductile material such as sheet-metal, by simple punching and folding operations, whereby it is shaped into a rectangular housing having open ends, the terminal folds 1 and 1' being overlapped and forming one of the broad sides of the housing. This housing is preferably of uniform interior dimensions throughout and is of proper height to receive accurately three folds or thicknesses of the material of which the shackle is made. The shackle is also formed out of light ductile material such as sheet-metal and may be made at a single punching operation. It is of proper width to fit accurately in the longitudinal pathway of the keeper and is formed with a plurality of locking members adapted for interengagement, and the spacial relationship of which is important and will be pointed out hereinafter. Adjacent what I will call its inner extremity, the shackle is formed with an upstruck resilient tongue or locking member 2, adjacent which is formed an aperture 4 through the material, constituting another locking member. At a suitable distance from the extremity of the strip the material may be scored transversely as at 5 to form a bending line, thereby determining the length of the terminal fold X of the shackle. This terminal fold is preferably substantially the same length as the keeper. Spaced apart from the line of fold 5 by a distance slightly in excess of the length of the shackle is a second scoring 6, which, together with the line of fold 5, determine the limits of the covering fold Y of the shackle. Spaced inwardly from the line of fold 6 the strip is provided with a second aperture 7 which constitutes another locking member and which is disposed in what I will term the inner fold Z of the shackle. The portion of the shackle comprising the folds X, Y and Z, which form the original means for attachment of the shackle to the keeper as hereinafter described, I will designate as the binding portion. Adjacent its other extremity the shackle is provided with a locking member, illustrated as a downwardly struck resilient projection 8, and inwardly of the strip from said projection with a similar locking member 9. These locking members are adapted for interengagement with the locking members 4 and 7 when the device is in assembled form. The members 8 and 9 are formed in the strip within a distance less than the length of the keeper, and at a proper distance from the outer extremity of the shackle the metal may be upstruck to provide detecting members 10.

In the original assembly of the device the terminal fold X of the shackle is slid into the keeper, the projection 2 being directed away from the overlapped folded portions 1 and 1'. The strip is then folded about

said overlapped portions so that the covering fold Y overlies the fold 1 on the exterior of the keeper. The strip is then inserted through the keeper again from the opposite end so that the inner fold Z overlies the terminal fold X. This disposes the parts in the relationship illustrated in Fig. 3, wherein the locking member 2 engages in the aperture 7 and prevents the unfolding of the binding portion of the shackle from around the overlapping portions of the keeper. This forms the article shown in Fig. 5, in which the keeper and shackle are permanently assembled.

When the seal is applied as by the shackle being passed through a suitable attaching device in the customary fashion, the free end W is returned and inserted intermediate the inner fold Z and the terminal fold X. When the free end is slid into position its inward movement is limited by the upstanding engaging member 2, and when the resilient locking members 8 and 9 pass the inner margins of the locking members afforded by apertures 7 and 4 respectively, having been compressed between the overlying folds of metal as the shackle end is slipped into place, they again spring outwardly by virtue of their resiliency, and engage through the said apertures. The resiliency of the terminal fold tends to press it into engagement with the entering end of the shackle, and thereby contributes to the certainty of engagement of the locking members. Retraction upon the inserted portion of the shackle will then definitely engage the said locking members 8 and 9 over the metal at the margins of the apertures 7 and 4, thus positively securing the shackle against withdrawal.

As assembled in this condition it will be observed that all of the folds of both the keeper and the shackle are securely and positively retained in place. Withdrawal of the inner fold Z is positively prevented by the engagement thereof with the locking member 8 and the engagement of locking member 2 with the end portion of fold W. Withdrawal of terminal fold X is positively prevented by the engagement of locking member 9 therewith and the engagement of locking member 2 with end portion W and engagement of locking member 8 with inner fold Z. Withdrawal of the parts is further prevented by the fit of the folds within the keeper and the short folding of the shackle about the flaps 1 and 1'. The engagement of the members also provides a double lock, and access to interlocked portions 9 and 4 from the end of the keeper is prevented by the enveloping folds of the shackle.

As is obvious from Fig. 4, the spacing of locking member 2 and the aperture 4 in fold X bears a relationship to the spacing of locking member 9 to the free end of the shackle, the spacing being such as to permit

the engagement of locking member 9 through aperture 4 when the extremity of the shackle is engaged by locking member 2. Likewise the spacing of aperture 7 relative to locking member 2 bears a relationship with the spacing of locking member 8 relative to the end of the shackle, the relationship being such as to permit the engagement of locking member 8 in aperture 7 when the 10 end of the shackle is in engagement with locking member 2. This device provides such a small, compact and neat sealing device as to preclude its being successfully tampered with or opened and replaced without showing evidences of the fact, both by virtue of the fact that all locking parts and closing seams are effectively covered and protected, and because of the fact that it affords no parts upon which a purchase may 20 be obtained to manipulate it illegally. It is obvious that because of the small amount and inexpensive quality of material required in the construction of the device, as well as the few numbers and simplicity of the 25 necessary operations involved, that it may be manufactured at very low cost.

Having thus described my invention, what I claim is:

1. A seal comprising a keeper formed of sheet material folded to form a housing with open ends and overlapping side portions, and a shackle inserted through the housing and having a binding portion folded about the overlapping wall portions thereof; said binding portion being provided with interengageable locking portions arranged for disposal within the housing whereby the binding portion is locked in folded relationship.

2. A seal comprising a keeper formed of sheet material folded to form a housing with open ends and overlapping wall portions, and a shackle including locking members disposable within the housing and interlocked portions folded about the overlapping wall portions and protecting the locking members in the housing from access from the ends thereof.

3. A seal comprising a housing open at opposite ends and a shackle extending through said housing and including locking members arranged for disposal within the housing; said shackle having a binding portion folded about a part of the housing and interlocked to permit withdrawal and a portion covering the locking members in the

housing to protect them against access from the end thereof.

4. A seal comprising a keeper in the form of a housing, and a shackle having a binding portion encompassing the housing and interlocked, said shackle having its terminal portions disposed within the housing; said terminal portions being provided with interengaging locking members. 60 65

5. A seal comprising a keeper in the form of a housing and a shackle having portions folded about a part of the keeper and overlapping within the keeper, said overlapping portions being provided with locking members, and said shackle including an end portion insertible between said overlapping portions for co-operation with the locking members thereon. 70

6. A seal comprising a keeper in the form of a housing and a shackle including a binding portion folded about a portion of the housing, said binding portion having portions disposed within the housing and provided with interengaging locking members effective to retain the shackle against movement out of the housing in either direction. 75 80

7. A seal comprising a keeper shaped as a housing with open ends and a shackle having a binding portion encompassing a portion of said housing and a free end insertible into the housing, said shackle including locking members engageable within the housing effectively to retain the binding portion and free end against movement out of either end of the keeper. 85 90

8. A seal comprising a keeper formed of sheet material folded to form a housing with overlapping portions, a shackle having a binding portion folded about the overlapping portions to secure and cover the edges thereof and locking portions arranged for effective engagement to hold the binding portion against unfolding. 95 100

9. A seal comprising a keeper shaped to provide a housing, and a shackle having a part folded to encompass a wall of the keeper longitudinally, said folded part including members overlapping within the housing and provided respectively with locking portions, and an end portion of the shackle being insertible into the housing between said overlapping members and having locking elements engageable with the locking portions thereof. 105 110
